Inventor: George A. Carpenter,

By Thomas G. Orwig, Attorney.

UNITED STATES PATENT OFFICE.

GEORGE A. CARPENTER, OF FORT MORGAN, COLORADO.

DEVICE FOR PUTTING MEDICINE INTO EYES.

SPECIFICATION forming part of Letters Patent No. 772,028, dated October 11, 1904.

Application filed November 13, 1903. Serial No. 181,102. (No model.)

To all whom it may concern:

Be it known that I, GEORGE A. CARPENTER, a citizen of the United States, residing at Fort Morgan, in the county of Morgan and State 5 of Colorado, have invented a new and useful Device for Putting Medicine into Eyes, of which the following is a specification.

My object is to provide means specially adapted for administering medicine to a person's eyes by induction for the purpose of strengthening weak eyes and curing diseases 10 of the eye.

My invention consists in a device constructed and applied and utilized as hereinafter set 15 forth, pointed out in my claim, and illustrated in the accompanying drawings, in which—

Figure 1 shows the flat side, and Fig. 2 the convex side, of one of the chambers adapted 20 for storing medicine therein. Fig. 3 is a transverse sectional view of the device and shows the manner of its construction. Fig. 4 shows two of the chambers connected in the manner that lenses of spectacles are connected to 25 be worn over a person's nose.

The numeral 10 designates a flat metal disk that may vary in size and form as desired. It is provided with a plurality of perforations in its central portion. A concavo-convex 30 plate 12 is provided with a central perforation and its circumferential edge swaged over the edge of the flat plate 10, as shown in Fig. 3, or connected therewith in any suitable way as required to produce a chamber 35 adapted for retaining a sponge or other suitable absorbent material, as shown in Fig. 3.

The two mating chambers are connected by a bridge-piece 13 and their outer ends provided with frames adapted to be connected 40 with a person's ears, so the device can be worn by a person in the manner spectacles are worn.

The absorbent material in the chambers is charged with a specific medicine by injecting

it through the perforations in the plates or 45 in any suitable way to be administered to the eyes of a person by induction at different intervals of time.

I am aware two flat perforated plates have been combined by providing one of the plates with a rim in such a manner that the rim would keep the two plates apart to produce a chamber in which an absorbent material was inclosed to retain medicine and to serve as a respirator; but in no instance has a chamber 55 been produced by a flat plate and concavo-convex plate by connecting their edges to produce a chamber as shown and described and specially adapted for administering medicine to an eye by induction in the advantageous manner set forth, and in no instance 60 have two such chambers been combined to be simultaneously applied and worn in the manner of spectacles.

Having thus described the purpose of my 65 invention, its construction, application, and manner of use, the practical utility thereof will be obvious to opticians and others familiar with administering medicine to a person's eyes. 70

What I claim as new, and desire to secure by Letters Patent, is—

In a device for administering medicine to a person's eyes by induction, a flat plate provided with perforations in its central portion 75 and a concavo-convex plate provided with a central perforation and the two plates united at their edges to produce a chamber, a second chamber produced in the same way, an absorbent material in each chamber, the two 80 chambers connected by a bridge-piece to fit over a person's nose and means for securing the device over a person's eyes, for the purposes stated.

GEORGE A. CARPENTER.
